Primary Examiner — Paula Greene*(74) Attorney, Agent, or Firm* — Brooks Kushman P.C.(57) **CLAIM**

The ornamental design for the earbud, as shown and described.

DESCRIPTION

FIG. 1 is a perspective view of the embodiment of the present invention;

FIG. 2 is a top plan view of the embodiment shown in FIG. 1; FIG. 3 is a bottom plan view of the embodiment shown in FIG. 1;

FIG. 4 is a left side view of the embodiment shown in FIG. 1; FIG. 5 is a right side view of the embodiment shown in FIG. 1;

FIG. 6 is a rear view of the embodiment shown in FIG. 1; and, FIG. 7 is a front view of the embodiment shown in FIG. 1 of the present invention.

The broken lines are for illustrative purposes only and form no part of the claimed design.
